UNITED STATES PATENT OFFICE

DAVID LEMIEUX, OF LEWISTON, MAINE

FEELER OR FILLING DETECTOR

Application filed April 20, 1927. Serial No. 185,178.

The present invention relates to a feeler or filling detector especially adapted for use on the Crompton and Knowles automatic magazine box loom.

5 An object of the invention is to provide a feeler, which is exceedingly simple in construction and may be attached to any standard loom with facility and expedition in place of the feeler or filling detector now customarily employed.

10 A further object of the invention is to provide a feeler or filling detector, which is acutely sensitive to quickly respond as soon as the supply of yarn on the bobbin is exhausted permitting the bobbin to doff in a manner well known in the art.

15 Another object of the invention is to provide a feeler, which is so durably constructed sufficient to withstand the strain imposed thereon which is readily detachable and which is adjustable.

20 Other objects of the invention will be apparent from the following description of the present preferred form of the invention taken 25 in connection with the accompanying drawings, wherein

Fig. 1 is a perspective view of a feeler or filling detector constructed in accordance with the present invention illustrating its application,

Fig. 2 is a similar view of the feeler finger per se,

Fig. 3 is a top plan view of a feeler or filling detector constructed in accordance with the present invention, showing the cover plate removed, and

Figure 4 is a perspective view of the feeler slide abutment.

In order to illustrate the application of the present invention, I have in Fig. 1 shown in perspective view a portion of a Crompton and Knowles automatic magazine box loom, which is generally designated 5. The loom embodies a shaft 5' which is equipped with the usual tension spring 52. One end of the shaft is engaged by an arm 6 of standard construction while the opposite end is engaged by an indicator plunger arm 6', which is pivotally engaged by the indicator plunger 62, said indicator arm and plunger being

of standard construction. The indicator plunger 62 is adapted for coaction with an actuator or chopper, not shown, for the purpose of holding the latter in an operative position when a transfer is to be made. The 55 feeler frame is detachably held on the stud 7 by means of a nut 9.

The feeler constructed in accordance with the present invention consists of a frame having a base portion 10, one of the lateral margins of which issues into a foot 11, which is provided with an elongated slot 12, the latter receiving the stud 7. The base portion 10 of the frame has a cover plate 12' superimposed thereon and detachably secured thereto so as to provide a casing through which the feeler slide 13 is movably mounted. The 60 feeler slide consists of an elongated bar, the ends of which project appreciably beyond the ends of the feeler frame and has one terminal 65 thereof reversely folded, as indicated at 14, to provide a housing in which the inner end 70 of the feeler finger 16 is pivotally mounted. The feeler finger consists of a relatively long, narrow bar, the outer or free end of which is 75 of arcuate configuration and is provided on the margin, which lies adjacent the bobbin, with serrations 31, the latter being engaged with the yarn on the bobbin to urge the feeler slide 13 forwardly and permit operation of

80 the actuator. A bolt which serves as the axis for the feeler finger 16, is indicated at 17, and is detachably arranged through the housing on the outer end of the feeler slide. It will be noted that the inner end of the feeler finger 85 is enlarged and the outer face of the enlargement obliquely disposed, as indicated at 18, this face slidably receiving one end of spring 19. The spring is wound about a shaft 20 mounted on the feeler slide and has the opposite end, from that which is engaged with the feeler finger terminal 15, engaged with a pin 21 as illustrated to advantage in Fig. 3.

90 The end of the feeler slide 13, opposite to that which carries the finger 16, is detachably 95 engaged, as indicated at 22, with the arm on the indicator plunger or feeler shaft of the loom. The feeler slide has a slot 23 formed therein through which a bolt 24 extends, the latter receiving an abutment plate 25 and be-

ing secured to the latter by a nut 26. One end of the abutment plate is extended to provide a finger 27, which is engaged by one end of a spring 28. The opposite end of said spring 5 is anchored on a stud 29, which is mounted in a recess 30 formed in the upper face of the base portion 10 of the feeler frame.

In use of this device, the serrated end of the finger is adapted to engage the yarn on 10 the bobbin to thereby hold the slide in a forward position and correspondingly permit the actuator to operate. As soon, however, as the yarn has been removed from the bobbin, the serrated end 31 of the finger impinges 15 against the smooth periphery of the bobbin thereby permitting the finger to flex against the resistance of the spring 19 and allowing the feeler slide to move rearwardly, which correspondingly moves the arm 6. This 20 movement urges the plunger 62 through the chopper or actuator to render the latter operative and permits the bobbin to doff in a manner well known in the art. It is well known that with feeler or filling detectors 25 now used, a certain amount of yarn remains on the bobbin with a consequent loss of material. It has been found, however, that the device of the present invention will not permit the bobbin to doff until after the yarn 30 has been completely exhausted from the bobbin with a very appreciable saving on each loom. It is possible to effect this result 35 because of the delicate nature of the mechanism employed especially the particular construction and manner of mounting the finger 40 and the particular manner of mounting the feeler slide 13. In addition, the springs 45 and 28 are almost completely housed to prevent foreign particles from in any way 50 retarding their effectiveness. Furthermore 55 the device is susceptible to quick adjustment when necessary.

Although I have above described the present preferred form of this invention together 55 with a preferred method of use, it is nevertheless to be understood that various changes may be made therein, especially in the details of construction, proportion and arrangement of parts within the scope of the claim hereto 60 appended.

I claim:

A feeler for looms including a frame engageable with the loom and equipped with a feeler slide, a feeler finger pivotally mounted 65 on one end of said slide and comprising a relatively long and narrow bar, the bobbin engaging end of which is remote from the slide and is equipped with serrations for engagement with the arm, the opposite end of 70 said finger being enlarged with one side thereof obliquely disposed, a spring anchored on the slide one end of which impinges against said oblique side of the feeler finger, means to normally urge said slide and finger 75 rearwardly toward the active bobbin, said

finger being flexed, against the resistance of the spring, to permit the slide to be urged rearwardly for transferring the bobbins when the supply of yarn on the active bobbin is completely exhausted.

DAVID LEMIEUX.
